UNITED STATES PATENT OFFICE.

FRANK C. WHITE, OF MERIDEN, CONNECTICUT, ASSIGNOR TO THE WILCOX & WHITE COMPANY, OF MERIDEN, CONNECTICUT, A CORPORATION OF CONNECTICUT.

MECHANICAL MUSIC-PLAYING INSTRUMENT.

1,103,854.

Specification of Letters Patent. Patented July 14, 1914.

Application filed November 22, 1912. Serial No. 732,802.

To all whom it may concern:

Be it known that I, FRANK C. WHITE, a citizen of the United States, residing at Meriden, County of New Haven, State of Connecticut, have invented certain new and useful Improvements in Mechanical Music-Playing Instruments, of which the following is a full, clear, and exact description.

My invention relates to an improved controlling means for mechanical music playing instruments, such as pianos and other keyboard instruments, the same being of particular value when employed in connection with an instrument of the so-called pneumatic player type.

In the accompanying drawings Figure 1 represents conventionally and diagrammatically certain parts of a player-piano with my invention embodied therein. Figs. 2, 3, 4 and 5 are detail views.

1 represents an action chest containing the action or striker pneumatics, not shown.

2 represents the choker box, so-called, containing suitable mechanism by which the tension of air within the action chest 1 may be modified at will and shifted either abruptly from low tension to high tension or gradually from said low tension to high tension, and vice versa, so that the notes will be struck with the desired force. The details of that particular form of controlling mechanism shown in said choker box 2 will later be described.

3 conventionally represents an exhauster. The exhauster 3 is connected with the action chest 1 through a suitable duct. Any suitable mechanism may be employed for creating a vacuum, or partial vacuum, at the exhauster 3.

4 represents a regulator pneumatic which in this instance is associated with the choker box 2, the purpose of said pneumatic being to maintain a uniform low tension of air in the action chest 1. This regulator pneumatic may be of the well known "Parker" type, shown for example in Parker Patent No. 473,388 and which is too well understood to require detailed description further than to state that it includes a movable member ex- tended by a suitable spring 5 and associated with a valve 6, which is located in the regulated air circuit leading from the action chest 1 to the exhauster 3. Under "low tension" conditions, air flows from the action chest 1

to a chamber 7 in the choker box 2. From the chamber 7 it flows into the regulator pneumatic 4, thence through the passage controlled by the valve 6 into a chamber 8, and thence to the exhauster 3.

9 is a passage controlled by a valve 10. This passage connects the chambers 7 and 8. When the valve 10 is open, there is a direct communication between the action chest 1 and the exhauster 3, so that the high tension in the exhauster 3 will be in direct communication with the action chest 1. It follows that when the valve 10 is closed, a regulated low tension will obtain within the action chest 1, and when the valve 10 is open, a high tension corresponding approximately with the tension in the exhauster 3 will occur within said action chest 1. The valve 10 is controlled by a suitable pneumatic indicated at 11.

12 is a small bleed-hole connecting the interior of the pneumatic 11 with the chamber 8, so that the valve 10 will normally stand open, as shown in the drawings.

13 is a duct which leads to the atmosphere, in this instance at two points, one point being controlled by a valve 14 and the other by a valve 15. In both instances, these valves may be in the form of springs which normally close the respective inlets controlled thereby. The valve 14 is manually controllable by a push-button 16, which may be conveniently located on the instrument so as to be easily engaged by the finger of the operator. When the button 16 is pressed, the valve 14 opens the duct 13 and atmosphere rushes in to the pneumatic 11, closing the valve 10, thus putting the action chest in communication with the exhauster 3 only through the passage controlled by the regulator valve 6. The valve 15 is controlled by a lever 17, which in this instance operates against a notched lever 18 with which the valve 15 is connected through the medium of a rod 19. The lever 17 is pivoted at 20 and is provided with a handle 21. When the handle 21 stands in the position shown in the drawings, the valve 15 is closed and the valve 10 is open, so that the tension of the exhauster 3 will obtain in the action chest 1. When the lever 17 and the handle 21 are shifted to the position indicated in dotted lines, the lever 18 will be slightly moved, opening the valve 15, flushing the pneumatic

11 and closing the valve 10 so that the regulated low tension will occur within the action chest 1.

At times it may be desirable to have the instrument operate automatically to shift the tension of air within the chest 1 from low to high, for the purpose of emphasizing solo or melody notes. To prepare for this, the handle 21 is shifted to the position indicated in dotted lines; wherein the valve 15 will hold open the duct 13 and thereby cause the valve 10 to stand normally closed instead of normally open. The means for securing an automatic shift in the tension is controlled from a tracker-board 22, which has the usual note perforations therein, and which has an additional expression perforation 23. This perforation 23 is connected by a duct 24 with a pneumatic 25, which controls a valve 26 which normally closes a large bleed passage in the duct 13, which bleed passage connects the interior of the duct 13 with the chamber 8. A note-sheet (not shown) traversing the tracker-board 22 normally closes the expression perforation 23 therein and the pneumatic 25 stands collapsed, closing the valve 26. When, however, an expression perforation in the note-sheet registers with the expression perforation 23 in the tracker, air rushes in, distending said pneumatic 25 and opening the valve 26, thus opening the pneumatic 11 through the large bleed passage to the vacuum within the chamber 8. It is obvious that the tracker perforation 23 is effective for automatic control only when the duct 13 is opened to atmosphere either by the valve 14 or the valve 15. When this condition obtains, the valve 10 is normally closed, and consequently if the valve 26 is opened under such conditions, the enlarged bleed passage controlled thereby operates to put the interior of the duct 13 and pneumatic 11 in quick communication with the vacuum within the chamber 8, the tension therein being sufficient to open the valve 10 either momentarily, or for so long a period as the expression perforation 23 in the tracker-board remains open, and for which moment, or period, the tension within the action chest 1 will correspond substantially with the tension in the exhauster 3 notwithstanding that 13 is open to atmosphere.

From the foregoing it will be seen that a normal low tension may be attained in the action chest 1 either by manually pressing down the button 16, or by swinging the handle 21 to the position indicated in dotted lines in the drawings, provided, of course, the perforation 23 is covered during such period. If at such time the perforation 23 is opened, the valve 10 will be automatically shifted to permit high tension. High tension may be normally secured at any time by allowing the button 16 to rise, or by

shifting the handle 21 to the position indicated in solid lines in the drawings. At times, it may be desired to further subdue the tone. This may be effected by shifting the hammer rest rail 27, which may be done through the medium of a pneumatic 28. In the drawings, a hammer rail 27 is conventionally shown as standing in its normal position. If, however, the pneumatic 28 is collapsed, the rest rail is shifted to a position nearer to the strings 29 so as to get the so-called "soft pedal" effect. This shifting of the hammer rest rail and hammers is controlled by a valve at the inner end of the handle 21, which latter is pivoted at 30 to the lever 17. The inner end of the handle 21 acts as a valve to cover the open end of a pipe or duct 31, which in this instance may also constitute the pivot 20 for the lever 17. Normally the valve end of the handle 21 closes the open end of the duct 31, said handle being held in that position by any suitable means. By pressing the outer end of said handle 21, the handle may be tilted and the duct 31 opened, whereupon, through the medium of a suitable pneumatic control located in a box 32, the pneumatic 28 is put in communication with the vacuum in the exhauster 3 through the pipe 33, causing said pneumatic 28 to collapse, shifting the hammer rail 27 to its "soft pedal" position. The handle 21 has its outer end exposed for manual manipulation, the same being located at some convenient place on the instrument so that it may be easily grasped by the hand of the operator. It will thus be seen that, with the parts thus far described, a quick shift may be effected from high to low tension, and vice versa, by the manipulation of the button 16 when the handle 21 stands in the position shown in solid lines, or it may be automatically effected from the tracker-board 22 when the handle 21 stands in the position shown in dotted lines. The pianissimo effect may also be further attained by pressing down on the outer end of the handle 21 to shift the hammer rail 27, as aforesaid.

In the present invention I provide means whereby when the instrument is set for the purpose of automatically causing the melody notes to stand out prominently, it is within the power of the operator to shade the accompaniment notes. While the accompaniment notes ordinarily under such conditions have been controlled and maintained at the low tension determined by the regulator 4, in the present instance I provide means whereby the operator of the instrument may manually vary this to vary the power of the accompaniment notes so as to get the most artistic effects. In the present instance I associate the accompaniment controlling means with the handle 21, so that by sweeping said handle 21 horizontally in an arc to the left

of the position shown in dotted lines in the drawings, the power of the accompaniment may be varied, for example, the power of the accompaniment notes may be increased by swinging the handle to the left and diminished by returning it again in a direction to the right until the dotted position is again reached. The means associated with the handle in this case comprises a by-pass valve 34, which controls a passage which connects the chamber 8 within the choker box with a chamber 35, which latter is also connected with the chamber 7. The passage controlled by the valve 34 is preferably V-shaped, as indicated in dotted lines in Fig. 2. The valve 34 is suitably connected, as by a rod 36, with an arm 37 projecting laterally from the lever 17. When the lever 17 and the handle 21 stand in the position shown in the dotted lines, the valve 34 will stand in a position ready to open the passage controlled thereby. If the handle 21 is now moved to the left, this opening of said passage will occur to a degree determined wholly by the degree of movement of the handle 21 to the left. This movement of said handle 21 opens the passage controlled by the valve 34 and puts the chamber 8 in direct communication with the chamber 7 through the chamber 35, thus putting the action chest 1 in direct communication with the exhauster 3 so that all notes struck at such a time will be struck with more than the regulated low tension vigor, the degree of increase being determined wholly by the degree to which the by-pass valve 34 opens the passage controlled thereby. This by-pass for the air should be so designed that even when fully opened the tension of air in the action chest 1, so far as the same is controlled by the valve 34, will be less than the highest tension secured through the passage 9, hence the solo notes will at all times stand out above the accompaniment notes, although the accompaniment notes may be sounded with more or less vigor. By this arrangement of mechanical parts, it is at once apparent that, by the manipulation of the single handle 21, the operator may effect a wide range of variation in musical effects.

I have, for obvious reasons, shown only one of the many forms which a complete operative mechanism may take to secure the desired effects, and I wish it to be clearly understood that I comprehend that many changes may be made in the various features of construction to adapt the mechanism to the various player mechanisms which are well known, without departing from the spirit or scope of this invention.

I have deemed it unnecessary to show the several action pneumatics by which the respective notes are sounded, since the same are too well understood to require detailed description or illustration. I have likewise

refrained from showing the pneumatic action mechanism other than by a conventional representation, it being understood that I may apply this invention to any appropriate, well known pneumatic action mechanism of the undivided or divided type. While I have shown the various valves and passages closely associated in the choker box, their particular relation may be changed, save that in the preferred form, the three passages, namely, the automatically regulated low tension passage, the valve-controlled high tension passage and the by-pass or shunt passage controlled by the by-pass valve, are arranged in parallel instead of in series. For convenience in expression, these three passages may be referred to in the claims as parallel wind-ways connecting the two ends of a main wind-way, one end of the main wind-way leading from the pneumatic action to the choker box, the other end of the main wind-way leading from the choker box to the exhauster.

What I claim is:

1. In a pneumatic music playing instrument, a pneumatic action mechanism, exhaust mechanism for creating a vacuum therein, a wind-way connecting said parts, including three parallel passages, a pneumatically controlled regulator valve for one of said passages, a manually controlled valve for another of said passages, and a valve for the third passage, with means for either manually or automatically operating said last mentioned valve, said means including a pneumatic for moving said valve to its closed or opened position, a duct leading from said pneumatic to the atmosphere and opening to the atmosphere at two points, a valve for each of said openings to the atmosphere, each of said valves being normally closed, a small bleed hole connecting said last mentioned pneumatic with said exhaust mechanism to exhaust the same and cause said valve to normally remain open when both of said valves to the atmosphere are closed, a larger bleed hole also connecting said last mentioned pneumatic with said exhaust mechanism, a valve for the large bleed hole, a pneumatic for controlling said valve, a tracker board having an expression perforation therein arranged to be opened and closed by a note sheet, and a duct leading from said last mentioned pneumatic to said tracker perforation, the operation of said valve for the large bleed hole being effective only when one of the manually controllable valves for the atmospheric openings in the duct for the high tension valve is opened.

2. In a piano player, a sounding device, a hammer therefor, expression controlling means including a movable hammer support for holding the hammer at different striking distances relatively to said sounding device, pneumatic mechanism including a high ten-

4

sion exhauster, a pneumatic for mechanically moving said hammer support, an action chest for controlling the mechanical operation of the hammer, a pneumatic regulator for automatically regulating the air tension between said action chest at a lower tension than in said exhauster, means for abruptly putting said action chest in direct communication with said exhauster to increase the 10 tension in said chest, means for manually varying the degree of the automatically regulated tension in said chest, and a single manually controllable device coöperating with all of said expression, controlling 15 means.

3. In a player piano, a sounding device, a hammer therefor, a pneumatic mechanism including an exhauster, a pneumatic action, a wind-way leading from said action to said 20 exhauster and including a plurality of passages arranged in parallel, a valve for one of said passages, with a pneumatic regulator coöperating therewith for automatically controlling the passage of air through said passage to provide a regulated tension in said 25 pneumatic action, a valve for another of said passages with means for fully opening or fully closing said passage by means of said valve, a manually controllable valve for the 30 third passage for varying the degree of opening therewith, with a single manually operable controlling device coöperating with the second and third of said valves for causing 35 the second valve to stand normally closed while the third valve is being opened, and with automatic means for opening the second valve even though the third valve is open.

4. In a player piano, a sounding device, a hammer therefor, a pneumatic mechanism 40 including an exhauster, a pneumatic action, a wind-way leading from said action to said exhauster and including a plurality of passages arranged in parallel, a valve for one of said passages, with a pneumatic regulator coöperating therewith for automatically controlling the passage of air through said passage to provide a regulated tension in said 45 pneumatic action, a valve for another of said passages with means for fully opening or fully closing said passage by means of said valve, a manually controllable valve for the 50 third passage for varying the degree of opening therewith, with a single manually operable controlling device coöperating with the second and third of said valves for causing 55 the second valve to stand normally closed while the third valve is being opened, and

with automatic means for opening the second valve even though the third valve is open, said automatic means including a tracker-board and a perforated note sheet. 60

5. In a player piano, a sounding device, a hammer, pneumatic action mechanism, an exhauster, a tracker-board, a pneumatic regulator for automatically controlling the tension of air within the pneumatic action mechanism, a manually operable valve for permitting the degree of tension within the action mechanism to be gradually varied, with independent means for abruptly increasing the air tension within said pneumatic action mechanism whenever the same is less than the tension which obtains in the exhauster, with a single manually controllable device coöperating with said manually 70 operable valve and said means for abruptly increasing said air tension within the pneumatic hammer action mechanism.

6. In a pneumatic music playing instrument, a pneumatic action mechanism, exhaust mechanism for creating a partial vacuum therein, a wind-way connecting said parts including a plurality of parallel passages, a pneumatically controlled regulator valve for one of said passages to vary the degree of opening thereof, a manually controllable valve for one of said passages also to vary the degree of opening thereof, and a pneumatically controlled valve for one of said passages to fully open or fully close said 85 passage, a pneumatic for the third valve being normally in communication with the exhaust and collapsed to cause said valve to open the passage controlled thereby under normal conditions, with means to open said 90 pneumatic to atmosphere to expand the same to close said valve so long as said pneumatic is open to atmosphere, a tracker-board having perforations therein arranged to be opened and closed by a perforated note sheet, 100 one of said perforations coöperating with the pneumatic for the third mentioned valve to abruptly cause the opening of said third valve when the same is closed, and a single manually operable means coöperating with the manually controllable valve and also coöperating with the third mentioned valve to cause the latter to normally close its respective passage while the manually operable valve is open. 105
